ELECTRON TUBE APPARATUS

Filed April 16, 1925

UNITED STATES PATENT OFFICE

SAMUEL RUBEN, OF NEW YORK, N. Y., ASSIGNOR TO RUBEN PATENTS COMPANY, OF NEW YORK, N. Y., A CORPORATION OF DELAWARE

ELECTRON TUBE APPARATUS

Application filed April 16, 1925. Serial No. 23,581.

This invention relates to a vacuum tube or electron tube apparatus; and it relates more particularly to apparatus of this type which utilizes the kinetic energy of the electron stream from the emission element under the control of electrical impulses impressed upon the grid or control circuit, to effect the movement of the anode element to make and break an external electric circuit, with means for compensating for tube vibration and for temperature changes in the surrounding atmosphere.

The invention comprises an improvement over those described in my prior and copending patent applications filed in the United States Patent Office February 4, 1922, April 11, 1922, and December 10, 1924, bearing Serial Numbers respectively, 534,213, 551,678, and 754,957 and United States Letters Patents 1,543,672, and 1,627,411 issued to me, upon various forms of vacuum tube relays, operating by the kinetic energy of the electron stream bombarding the anode element of the tube, and for certain uses, is an improvement upon the devices described therein. The object of this invention is to provide a vacuum tube relay sensitively responsive to the electron stream bombardment upon the anode element, more sturdy in design and less susceptible to tube vibration and atmospheric conditions than those of my prior inventions. It is particularly in respect to the means provided for compensating for the effects of tube vibration and atmospheric conditions upon the movement of the anode that this invention lies.

As the electronic bombardment of the bimetallic anode varies under the control of electrical impulses impressed upon the grid circuit, the temperature of the anode varies, thereby causing a movement of the contact point mounted thereon. Such movement is effective in opening and closing the gap included within the vacuous space, in an external circuit. Due to the high vacuum in this tube, even with a current of high potential, in the opening and closing of the gap between the contact points there is no premature arcing or sparking.

A single bimetallic expansion anode mem-

ber, initially adjusted with respect to the gap between the two contact points in the external circuit may require frequent adjustment to insure uniform anode movement, if the temperature changes of the surrounding atmosphere are sufficient to affect the position of the anode at the end to which the contact point is attached. I overcome this objection in a manner hereinafter described.

By the terms of my invention, two thermosensitive bimetallic expansion elements, differentially connected, are mounted so that there is no movement of the contact point unless one of the elements or members is independently heated or cooled. The element to be so affected acts as the anode to be bombarded by the electron stream from the cathode emission. These anode members are constructed of two suitable metals or alloys having widely different coefficients of thermal expansion, such, for instance as brass and an alloy of nickel and steel. As these members are differentially connected, external temperature conditions, affecting each alike, the effect upon each is neutralized by that on the other, and there is no movement of the contact point.

In the apparatus of my invention the members are so arranged that the electron stream bombardment is upon one arm or member only, its action or movement being governed accordingly under the control of the received electrical impulses impressed upon the grid or control circuit. Therefore, unless so bombarded, the contact points are separated by a constant gap, irrespective of tube vibration and atmospheric temperature changes. As the bimetallic members are mounted, each with one end fixed and with the other ends differentially or oppositely connected, any normal vibration of the apparatus and any normal atmospheric temperature variations fail to produce a movement of the movable contact point, the tendency of one arm or member being off-set or counteracted by that of the other. However, the anode is entirely free to move at one end under the influence of the electron stream bombardment.

The principles of the invention can best be further explained in connection with a cer-

tain illustrative embodiment thereof, shown in the accompanying drawings, in which,

Fig. 1 is a diagrammatic view of the vacuum tube and its various elements; Fig. 2 is a similar view of the grid and anode elements; and Fig. 3 represents a radio receiving circuit, also a bell ringing circuit, in which the vacuum tube is connected.

Referring to Fig. 1, V is an evacuated container of glass or other suitable material, exhausted to a degree at which substantially a pure electron discharge is obtained. At 1 is an electron emission filament, supported by conducting rod 1_a and at 2 is a grid or modulating element supported by conducting rods 2_a. At 3 is an anode or plate element, and 3_a a differentially related element, both 3 and 3_a being composed of a bimetallic expansion couple combination, rigidly mounted at the lower ends by ferrule 5 on glass rod 6, the bimetallic couple combination being composed of brass and an alloy of steel and nickel. Mounted on the upper end of member 3_a is contact point 3_b, opposite to and arranged to contact with contact point 4 of the external bell ringing circuit, the leads of which, L₄ and L₅ enter the tube through the glass seal. The stationary contact point 4, is mounted on nickel ferrule 4_a attached to glass rod 6. Also extending through the glass seal of the tube are cathode leads L₁ and L₂, grid lead L₃ and anode lead L₄, which latter also constitutes a portion of the external circuit.

Fig. 2 shows the detail of the grid arrangement and the adjacent arm 3 of the anode element.

Referring to Fig. 3, which illustrates a radio receiving circuit and an external bell ringing circuit, at C is a variable condenser for selectively tuning the circuit to the desired incoming electrical impulses impressed upon the grid circuit. At B_c is a battery for negatively charging the grid, B_a being the source of energy for heating the cathode to emission temperature, regulated by resistance R, the potential for the cathode-anode circuit being supplied by battery B_b. At T is a telephone receiver, across which is connected by-pass condenser C₁. G represents a bell in the external circuit, the energy for which is supplied by source B. The impedance of the movable anode circuit is low enough to allow the inclusion of a telephone receiver and the reproduction of signals of audio frequencies.

In operation, the bombardment of electrons from the filament to the anode produces a temperature rise which upsets the differential balance between 3 and 3_a and thereby closes the contact gap. By the use of suitable negative bias potential upon the grid, the emission is sufficiently decreased to allow the separation of the contacts, due to the reduction of the bombardment, and upon the reception of the incoming electrical impulses applied to the grid circuit, the effect

of the negative bias grid potential is neutralized and there is sufficient increment of the electron emission to again close the contacts.

What I claim is:

1. An electrical discharge relay tube having an incandescent cathode, a control electrode, an anode comprising a bimetallic expansion couple, another bimetallic expansion couple and a circuit-making-and-breaking means located within said tube, said means being operable by the movement of the anode in response to variations of its temperature by changes in its electronic bombardment from the cathode.

2. An electron discharge relay tube comprising an envelope, a cathode, a control electrode and an anode comprising a bimetallic expansion couple, contacts and a support, one of said contacts being mounted upon the anode and the other of said contacts being mounted upon the support, one of said contacts being moveable in response to the electronic bombardment of the anode.

3. An electrical discharge relay tube containing within its vacuous space a cathode, a control electrode, contacts, an anode comprising a bimetallic expansion couple supporting one of said contacts and another bimetallic couple positioned to maintain a gap between said contacts, independent of temperature changes of the anode, other than those due to the electronic bombardment of the anode.

In testimony whereof, SAMUEL RUBEN has signed his name to this specification this 14th day of April 1925.

SAMUEL RUBEN.
